UNITED STATES PATENT OFFICE.

IVEN GEORGE SMEDBERG, OF MINNEAPOLIS, MINNESOTA.

EXERCISING SWING.

Application filed February 12, 1926. Serial No. 87,776.

My present invention has for its object to provide an exercising swing, and to this end, it consists of the novel devices and combinations of devices hereinafter described and defined in the claims.

In the accompanying drawings, which illustrate the invention, like characters indicate like parts throughout the several views.

Referring to the drawings:

10 Fig. 1 is a view principally in front elevation, with some parts sectioned on the line 1—1 of Fig. 2;

15 Fig. 2 is a view partly in side elevation and partly in vertical section, taken on the line 2—2 of Fig. 1;

Fig. 3 is a fragmentary view partly in plan and partly in horizontal section; and

20 Fig. 4 is a detail view with some parts sectioned on the line 4—4 of Fig. 1, on an enlarged scale.

The swing, as shown, is carried by a frame comprising a rectangular top member 5 supported on laterally spaced pairs of legs 6. The legs of each pair 6 are in converging relation and are rigidly connected at their tops by a tiebar 7. The swing has a seat 8 that rests on set-screw-equipped collars 9 on a pair of suspending members 10 carried by a rock shaft 11, the ends of which are journaled in the tiebars 7. The suspending members 10 are in the form of metallic tubes arranged to turn on their longitudinal axes by having their upper end portions mounted in eyes in the rock shaft 11 and their lower end portions mounted in bores in the seat 8. Set-screw-equipped collars 12 are applied to the upper ends of the suspending members 10, loosely rest on the rock shaft 11 and support said members therefrom.

45 A yoke-like foot rest 13 is attached to the suspending members 10 by having its arms inserted into the lower ends of said members, and which members are swivelled to said arms by set screws 14 having threaded engagement with said members and extending into circumferential channels in said arms.

The swinging members 10, above the seat 8, are provided with crank-acting hand holds 16 having variable throw. Each suspending member 10 is formed from two tube sections, the inner end portions of which are bent laterally outward. The crank-acting hand holds 16 are in the form of U-shaped rods, the arms of which are inserted into the laterally bent inner ends

of the suspending members 10 and adjustably secured thereto by set screws 17.

To set up swinging movement of the swing under the action of the turning movement of the suspending members 10 by the crank-acting hand holds 16, there are provided for each suspending member pulling connections that are reversely extended in the plane of the swinging movement of the swing. These pulling connections for the respective suspending member 10 include a crank arm 18 secured thereto, above the rock shaft 11, and a pair of cables 19 having one of their ends attached to the crank arms 18 and their other ends attached to a pair of connected ears 20 swivelled to said supporting member, the intermediate portions of said cables being arranged to run over anchors in the form of guide sheaves 21. The crank arms 18 project substantially diametrically opposite the cooperating crank-acting hand holds 16 and the pairs of ears are held between opposing set-screw-equipped collars 23 on the suspending members 10. The guide sheaves 21 are journaled in forks on nut-equipped bolts 24 that extend through the vertical members of the frame member 5. Coiled springs 25 are compressed between the frame member 5 and nuts on the bolts 24, and yieldingly hold the guide sheaves 21 to take up slack in the cables 19.

By adjusting the collars 9 on the suspending members 10, the seat 8 may be raised or lowered in respect to the foot rest 13, and by radially adjusting the crank-acting hand holds 16 in respect to the suspending members 10, the throw thereof will be varied, at will.

It will be noted that the crank arms 18, are provided with a multiplicity of longitudinally spaced holes in which the respective ends of the cables 19 may be secured to vary the throw of said crank arms. By raising or lowering the ears 20, by means of the collars 23, the leverage of the pulling connections on the suspending members 10 may be varied, at will.

The operation of the exercising swing may be briefly described as follows:

The person wishing to take exercises sits on the seat 8 with his feet on the foot rest 13 and takes hold of the crank-acting hand holds 16. Then, by swinging said hand holds to turn the suspending members 10 back and forth, the crank arms 18 are oscillated to produce the required pulling action

to set up swinging movement of the swing.

The action obtained by the improved swing is substantially like the action obtained in rowing and is especially well 5 adapted for developing the chest, back and arms.

What I claim is:

1. An exercising swing comprising an overhead rock shaft, a pair of carrier-suspending members mounted on the rock shaft to turn on their longitudinal axes, and pulling connections including cranks attached to the suspending members, said suspending members having cranks by which they may 10 be turned for operating the pulling connections to set up swinging movement of the swing.

2. An exercising swing comprising an overhead rock shaft, a pair of carrier-suspending members mounted on the rock shaft to turn on their longitudinal axes, and reversely acting pulling connections attached to the suspending members, said suspending members having cranks by which they may 20 be turned for operating the pulling connections to set up swinging movement of the swing.

3. An exercising swing comprising an overhead rock shaft to a pair of seat-suspending members mounted on the rock shaft to turn on their longitudinal axes, and pulling connections including cranks attached to the suspending members, said suspending members having crank-acting hand holds 30 by which they may be turned for operating the pulling connections to set up swinging movement of the swing.

4. The structure defined in claim 3 in which the cranks in said connections have a 40 variable throw.

5. The structure defined in claim 3 in which the crank-acting hand holds have a variable throw.

6. An exercising swing comprising an

overhead rock shaft, a pair of seat-suspending members mounted on the rock shaft to turn on their longitudinal axes, and reversely acting pulling connections including cranks attached to the suspending members, cables having one of their ends attached to 45 the suspending members and their other ends attached to said cranks, and anchors over which the intermediate portions of the cables are arranged to run, said suspending members having crank-acting hand holds by 50 which they may be turned for operating the pulling connections to set up swinging movement of the swing.

7. The structure defined in claim 6 in which the ends of the cables attached to the 55 suspending members may be raised or lowered.

8. The structure defined in claim 6 in which the anchors are yieldingly held.

9. The structure defined in claim 3 in 60 further combination with a foot rest secured to the suspending members by swivel connections.

10. An exercising swing comprising an overhead rock shaft, suspending members 70 carried by said shaft, a seat carried by the suspending members, said members being free to turn on their longitudinal axes in respect to said shaft and seat, and pulling connections including cranks on the suspending members, swivelled ears adjustably attached to the suspending members, anchors, and cables having one of their ends attached to said cranks and their other ends attached to said ears, with their intermediate portions arranged to run over said anchors, said suspending members having crank-acting hand holds by which they may 75 be turned for operating the pulling connections to set up swinging movement of the 80 swing.

In testimony whereof I affix my signature.

IVEN GEORGE SMEDBERG.
